DESIGN FOR A COMBINED SOAP DISH AND GRAB BAR

Geraldine A. Smoyer, Allentown, Pa., assignor to Brey & Krause Manufacturing Company, Allentown,
Pa., a corporation of Pennsylvania

Application April 10, 1934, Serial No. 51,368

Term of patent 7 years

To all whom it may concern:

Be it known that I, GERALDINE A. SMOYER, a citizen of the United States, residing at Allentown, in the county of Lehigh and State of Pennsylvania, have invented a new, original, and ornamental Design for a Combined Soap Dish and Grab Bar, of which the following is a specification, reference being had to the accompanying drawing, forming a part thereof:

I claim:

The ornamental design for a combined soap dish and grab bar substantially as shown.

GERALDINE A. SMOYER,
